L. T. SAWYER

HAIR RETAINER OR COMB

Filed July 24, 1926

FIG. 1.

Inventor.
Lester Thorndike Sawyer

UNITED STATES PATENT OFFICE.

LESTER THORNDIKE SAWYER, OF FITCHBURG, MASSACHUSETTS.

HAIR RETAINER OR COMB.

Application filed July 24, 1926. Serial No. 124,659.

This invention relates to a comb or retainer designed to be worn in the hair. It is the object of the invention to provide a construction for such articles which will 5 permit the comb or retainer to be easily inserted in the hair and to be securely held from displacement therein.

A further object of the invention is to provide a device of this character in which 10 no loose or additional parts such as pins, latches, or clasps are required to hold the device in position.

With these general objects in view, an 15 important feature of the invention relates to the provision of a comb-like structure having relatively small teeth so constructed that portions thereof will yield laterally to firmly grip and hold a strand of hair inserted between adjacent teeth.

20 A preferred form of the invention and certain modifications thereof are shown in the drawings and will be more specifically set forth in the appended claims.

Referring to the drawings

25 Fig. 1 is a front elevation of one form of my invention;

Fig. 2 is a sectional end view, taken along the line 2-2 in Fig. 1;

Fig. 3 is a partial front elevation, showing 30 the device in use; and

Fig. 4 is a similar view of a modification.

Referring particularly to Figs. 1 to 3, I have shown my improved comb or hair retainer as comprising a supporting portion 35 or back 10 having a plurality of relatively small teeth 11 projecting therefrom. As shown in Fig. 1, the teeth 11 are provided with relatively large elongated central openings 12, each extending throughout a 40 major portion of the length of a tooth.

These openings 12 may be formed by slitting the teeth and bending the side portions outward or they may be formed by punching the openings in suitably shaped teeth. In any 45 event, the side walls 13 of the teeth are relatively thin and quite resilient.

When in normal position, the side walls 13 of adjacent teeth are substantially in engagement with each other but when the 50 device is inserted in the hair, the side walls 13 yield readily, causing the teeth to as-

sume a flattened appearance as shown in Fig. 3, and firmly gripping and retaining the hair H between the adjacent sidewalls. The end portions or points 15 of the teeth 55 are closed and smoothly finished, like the teeth of an ordinary comb. Special end teeth 16 may also be used to provide a more finished appearance at the ends of the comb if desired.

60 While the comb may be made of any suitable material, I have found that pyroxylin or other similar resilient sheet material is well fitted for use in my improved retainer.

65 It will be noted while the device is peculiarly adapted and very effective for the purpose designed, it nevertheless closely resembles an ordinary comb and cannot be distinguished therefrom when in position 70 on the head of the wearer.

In Fig. 4, I have indicated a modification in which the teeth 25 are each formed of a single piece of wire, bent to provide a closed point and a central opening, and having the 75 ends inserted into a back portion 26. This form of the device is very similar in its operation and advantages to the form shown in Fig. 1.

Having thus described my invention and 80 the advantages thereof, I do not wish to be limited to the details herein disclosed otherwise than as set forth in the claims, but what I claim is:

1. A hair retainer comprising an elongated back, and a plurality of relatively 85 small teeth mounted closely adjacent thereon, all of said teeth having closed smooth points and certain of said teeth having relatively large elongated openings 90 throughout the major portion of their length and having relatively thin resilient side portions, the sides of adjacent teeth being normally in substantial engagement with each other, and said resilient side portions being yieldable to permit insertion of hair between said teeth and to grip and retain the hair thus inserted.

2. A hair retainer comprising an elongated back, and a plurality of relatively 100 small teeth mounted closely adjacent thereon, all of said teeth having closed smooth

points and certain of said teeth having relatively large elongated openings throughout the major portion of their length and having relatively thin resilient side portions, the sides of adjacent teeth being normally in substantial engagement with each other, and said resilient side portions being

normally curved outwardly to effect such engagement, but being flattened when a strand of hair is inserted between said teeth and yieldingly engaging and retaining a strand of hair thus inserted.

LESTER THORNDIKE SAWYER.
